UNITED STATES PATENT OFFICE

RICHARD FITZ POWER, OF HAMPSTEAD, LONDON, ENGLAND, ASSIGNOR TO MORLAND
AND IMPEY LIMITED, OF NORTHFIELD, BIRMINGHAM, ENGLAND

VISIBLE INDEX

Application filed August 16, 1930, Serial No. 475,814, and in Great Britain September 28, 1929.

This invention relates to visible indexes and has more especial reference to vertical visible indexes of strip form, although also applicable to visible card indexes.

5 The main object of the invention is to provide an inexpensive assembly, the components of which will be secured when positioned, while being readily removable and replaceable when required.

10 A second object is to ensure the correct alignment of the assembled elements of the index, at the same time preventing any possibility of objectionable overlap hitherto present.

15 Further and favourable objects will appear from the following description.

Essentially the invention includes a strip of material preferably stout paper or cardboard, from either side of which project lugs 20 having one or more lateral projections, these lugs engaging retaining members on the index base so as to secure the strip in position.

When applied to strip indexes such a strip carries the index matter and conveniently has 25 a pair of T-shaped lugs symmetrically located on its lower edge and three lugs on its upper edge, the central lug being T-shaped and the two end lugs having inward projections, the laterally projecting portions of all the lugs 30 being arranged to engage under vertical retaining members, say in the form of ribands on the index base.

An interlocking assembly is thus obtained on a plurality of the strips being mounted on 35 a common base and several strips can be assembled uniformly in immediate contact with each other, the upper central T-shaped lug of one strip lying under the strip next above and the two lower T-shaped lugs of the second mentioned strip lying under the first strip so that an interlocking assembly is obtained and positive alignment of the cards assured.

To facilitate manipulation the ends of the 45 strip and the edges of the lugs are preferably curved, and in order that entries may be made on the strips in a typewriter the strip width is based on the customary typewriter spacing, corresponding say to double or treble typewriter spacing, according to the amount of

index matter which it is required to include on the strip.

In order that typing on the strip may be simplified a typing sheet can be provided having vertical slots arranged to accommodate the lugs on a strip or a number of strips which are thus secured to the sheet, and the sheet can then be inserted in a typewriter in the ordinary fashion and the desired matter typed on the index strips.

The index strips may be punched in quantities from stout paper or card, preferably the punches are not completed in order that a number of strips can be sold as an integer and inserted direct into a typewriter for the 60 impression on the strips of the required index matter.

When applied to a visible card index the index cards can be attached to the strips say by adhesive or by the T-shaped lugs on the 65 strips passing through slots in the cards, or the supported edge of the card may be arranged with the T-shaped lugs forming the 70 essence of the invention. With either arrangement a cheap and efficient construction 75 is attained which does not require a rigid support or base, an ordinary sheet of stout paper or card having slots for engagement by the T-shaped lugs being adequate for the 80 purpose and being reinforced transversely by the index strips.

The arrangements according to the invention lend themselves readily to the assembly of a plurality of visible indexes in book form owing to their small overall thickness, although preferably the assembled units of the index are raised somewhat from the base to facilitate manipulation.

Reference will now be had to the accompanying drawings which illustrate the invention by way of example, and in which:—

Fig. 1 illustrates a strip according to the invention;

Fig. 2 shows a typing sheet for holding strips while passing through a typewriter.

Fig. 3 shows a holding sheet proper in the form of a loose leaf of a book.

Figs. 4-9 are end views of several arrangements for mounting a card on an index strip.

Fig. 4 shows a strip arranged as a holder 100

for an index sheet or card attached to it by adhesive.

Fig. 5 shows a construction in which T-shaped lugs according to the invention are pressed out from the card.

Fig. 6 illustrates a combination of the arrangements shown in Figs. 4 and 5.

Fig. 7 shows an index holder combined with a double index sheet having slits along its fold and in the face of the undersheet.

Fig. 8 is an index holder with a single sheet provided with a slotted flange to take the lower lugs.

Figs. 9 and 10 show a section and front view respectively of a single sheet with a slit in its front face.

Fig. 11 is a front view showing the double sheet as shown in Fig. 7, mounted on the index holding strip.

Fig. 12 illustrates a method of manufacturing the index strips or holders in a form suitable for typing entries thereon in a typewriter.

Fig. 13 is another form of a sheet adapted for use on a typewriter.

Fig. 14 shows a face view of the strip as a holder integrally attached to an index card as in Fig. 5.

Figs. 15-22 are views of several arrangements of an index in book form.

Fig. 15 shows an index in book form with a distancing support frame carrying the holding ribands for the strips, mounted on each cover.

Fig. 16 is a section on the line A—A of Fig. 15.

Fig. 17 shows an index in book form including a distancing support frame with ribands on both sides thereof, the frame being hinged to the covers to form a single page.

Fig. 18 is a section on the line B—B of a page of the device shown in Fig. 17.

Fig. 19 illustrates a form of the invention in which a collapsible distancing support frame is mounted on each cover.

Fig. 20 is another construction of the form shown in Fig. 19.

Fig. 21 is a vertical section through the covers shown in Fig. 19 shown open; and

Fig. 22 is a vertical section through the same shown closed.

Referring to the drawings, Fig. 1 is a face view of about full size of a strip, or holder, having the body portion 1 preferably of such a depth from top to bottom as to correspond with the standard spacing of an ordinary typewriter when a series of these are put together. Along the top edge of the strip 1 are the lugs 2, 3 with the single horns 4, 5 and a central lug 6 with double horns 7, 8, while on the lower edge are two lugs 10, 11, the former with the double horns 12, 13, and the latter with the double horns 14, 15.

It will be noted that the lugs with their

horns or projections are alternately arranged or in staggered relation on the two longitudinal edges of the strip or body portion 1.

The ends of these strips are preferably rounded as shown, but may be square where desired.

Fig. 2 illustrates a typing sheet. This consists of an ordinary sheet of paper 20 formed with a series of slots or spaces 21, 22, 23, 24, 25 from near its bottom edge to near its top edge. Threaded in these slots is a series of strips such as 1, 9, 17 by means of the lugs 2, 3, 6, so that they underlie the top panel of the sheet 20 while the horns 12, 13, 14 and 15 of lugs 10, 11 underlie the strips of paper between the spaces 21 to 25.

In the case of the next strip 9 the horns of the lugs corresponding to 2, 3, 6 underlie the strip 1, consequently the main part of the edges of the strips 1 and 9 abut against each other while the lugs 10, 11 of 1 underlie the strip 9 so that it cannot ride up on the strip 1.

The sheet 20 may be threaded until strips occupy the whole length of a slot such as 21, it being noted that the slots 21 and 25 are narrower than the slots 22, 23, 24 in order that the side strips 18, 19 of the sheet may overlie the ends of the series of strips.

When full, or partially full, this sheet 20 may be placed in a typewriter and any entries needed to be written on the several strips may be typed thereon in precisely the same way as in taking any other sheet through a typewriter, it being important to note that the width of the strip is made to suit the standard spacing mechanism of the typewriter so that movement from one strip to the next corresponds to moving a paper sheet for one, two, or three spacing, or the like, as may be desired; the strips 1, 9, 17 and the like are made with one space depth, two space depth, and so on.

Fig. 3 shows a holding sheet, and as illustrating the point just noted the top strip 31 is wider than the adjoining strip 32 in order that it may have more lines than one typed thereon, but so that the spacing mechanism of a typewriter brings the body portion of the strip 32 to correct position for typing when reached.

This holding sheet, or index sheet 30, as it is hereinafter called, can be a stiff sheet having the slots 33, 34, 35 cut bodily from its face, as in Fig. 2, but preferably these slots are cut from a second strip 36 mounted by fixing its connecting end portions 36, 37 to the back sheet 30.

The strips 31, 32 are mounted in the slots 33, 34, 35 precisely as shown in Fig. 2, except that the ends of the strips in this case do not need a slot for engaging them, as they are not expected to pass through a typewriter after insertion in the index 30. As in Fig. 2 the horns of the lugs are engaged, thus preventing one strip from riding up or overlapping.

the next as regards its body portion carrying the typed matter.

5 A series of these sheets 30 may be mounted in book form either loose-leaf or otherwise, and form a most advantageous visible index of small volume.

10 In a modification a central zone of the superimposed ribands 38, 39, 40, 41 may be attached by adhesive, staples, or the like, to the back sheet 30 with a view to stiffening the same, the chain dotted lines as shown along the centre of these ribands being intended to indicate the adhesive.

15 Figs. 4 to 6 illustrate modifications in which the index strip carries a single sheet.

In Fig. 4 the sheet 48 is attached by adhesive along its top to the body portion 1 of a holder strip.

20 In Figs. 5 and 14 the sheet 49 is made integral with the strip portion 1, holes being cut out therefrom as at 50 to allow of a lug such as 10 being enclosed, and so that the sheet along with the holder may lie flat.

25 Fig. 6 is the same structure as Fig. 4, except that the face of the sheet is applied—by adhesive or the like—to cover also the face of a separate strip 1 including its lugs, and the holes at 50 are cut from the sheet opposite lugs such as 10 on the holder strip.

30 Fig. 9 shows a sheet 42 with slits 43 in it near and parallel to its upper edge which will be attached to its strip holder by threading the lugs 2, 3, 6 through the slits 43 as shown in Fig. 10 (drawn to a somewhat reduced scale).

35 Referring now to Figs. 7 and 11, a strip 1 is indicated having the lugs 2, 3, 6 (as in Fig. 1) threaded through slits in the fold of a double index sheet 44, 45, the under sheet 40 45 being also provided with slits such as 46 through which the lugs 10, 11 are threaded in order to prevent the sheets 44, 45 riding up on the lugs 2, 3 when mounted as one of a series together.

45 The top sheet 44 is broken away as shown in order to show this lug through the underneath sheet, and it should be understood that, as shown in Fig. 8, if a double sheet is not required, a folded margin 47 only need be provided on a single sheet 44 for the reception of the lugs 10, 11.

50 Since, in fact, when a series of holders and sheets are together one cannot ride up on another on account of the action of the lugs, it is not absolutely necessary to have the lugs 10, 11 threaded through the rear face of the sheet 44, 45, which consequently can be made either with a folded margin similar to 47, only narrower and not slitted, or as shown 55 in Fig. 10.

55 Fig. 12 shows a series of the index strip units such as 1, 9, 17 manufactured by stamping separating perforations such as 52 from a sheet and so as to form lugs, say 2, 10, 6, 11, 3, upon each side of a strip as required,

and with easily broken detachment sections such as 53, 54, 55, between the several strip units.

The units are arranged with the writing-receiving portion at a standard spacing (or 70 multiple spacing) distance apart from each other as found on the normal typewriter; succeeding strips or records can thus be typed by advancing the sheets, line by line, in a typewriter in the usual way; by having lugs 75 such as 10, 11 cut from an otherwise empty perforation such as 52 a considerable saving in material is effected, and a better rigidity of the sheet is present when used for such purposes as typing on a typewriter. 80

Incidentally, some part of this rigidity is obtained by reason of the detachment sections being located on an irregular line such as XY.

To improve this rigidity in passing 85 through a typewriter the sheet may advantageously be completed with a border such as 57, particularly along the sides.

In practice such a sheet might be in the form of a long belt or band which would 90 even pass over a roller coming from a wall or other support in order that any particular unit of the series may easily reach typing position in a typewriter.

Referring to Fig. 13 it will be seen that 95 it is substantially the same as Fig. 12 except that the side marginal edges 57 are omitted, and the detachment sections such as 58 are shown at the ends of a lug such as 59 in order to prevent possibility of the projecting ends 100 being displaced.

Referring to Fig. 15 which shows an index in book form it will be seen that the ribands 38, 39, 40, 41 are stretched across distancing support frames 60 respectively mounted on a 105 cover 61, of the index, each frame and cover being integrally formed and the covers 61 being hinged together at 62. Index strips such as 1, 9 are held as before by the ribands, which are preferably made of thin metal and 110 they are slidable thereon, the purpose of the distancing support frames which raise the ribands from the covers being so that the fingers of an operator desiring to detach a strip, such as 17, may have the space behind the 115 ribands available for the fingers in order to facilitate the detachment.

This will be evident by referring to Fig. 16, which illustrates the amount of space beneath the ribands available for this purpose. 120 In Figs. 17 and 18 a similar construction to that shown in Fig. 15 is illustrated, except that the frames 60 are not mounted as one with the covers 61, but instead, separate frames 73 (corresponding to the frames 60) are employed, the said frames being hinged at 62a to the hinge connection 62 of the covers 61; each frame 73 carries two sets of ribands, one set such as 38, 39, 40, 41 being attached to the one side of the frame, and a fur- 125 130

ther set such as 64, 65, 66, 67 being secured to the opposite side of the frame. The two sets are shown clearly in Fig. 18 with the frame 73 between them.

5 In Fig. 17 the series of strips such as 1, 9, 17 are kept in place when the index is full by the sliding plate 70. This plate has recesses 71, across which are depressed strips of the material cut so that they will slide under-

10 neath the ribands such as 41, and will slide thereon so that the plate 70 will fill the clearance space needed at the base of an index to allow of the individual index strips being movable for substitution, or otherwise.

15 Such a plate 70 may advantageously be provided with depressed portions 72, which will catch on the lower inner edge of the frame 60 or 73 when in operative position when the index is full.

20 It may be noted that the plate 70 can be drawn over the lower edge of the frame, as shown by the position of the plate 70 on the left of Fig. 17.

The plates 74 at the upper end of the 25 frames are the usual hinged plates for writing a card upon when taken from a file.

Figs. 19—22 show two arrangements of index in book form in which the necessary space underneath the ribands is obtained by collapsible distancing support frames so that the index closes into a minimum amount of space. In Fig. 19, each frame comprises distance pieces such as 75, which are cut from a layer 76 of cardboard or other material of suitable flexibility and stiffness forming part of a cover 61. The distance pieces such as 75 leave recesses 77 in the layer 76, these recesses being occupied by the distance pieces 75 when the index is closed.

25 The ribands 38, 39, 40, 41 are laid across the distance pieces 75 and are attached to end pieces 78, 79, which are secured either by adhesive or by fixing blocks 81, to the upper surface of a raising member 80 fixed to the 30 cover hinge 82. The distance between the upper surface of the member 80 and the cover hinge 82 is such that when the index is closed, the end pieces 78, 79, are moved sideways relatively to the covers 61, thus causing the distance pieces 75 to move into the recesses 77.

Fig. 21 shows the index open flat in operative position for the insertion of index strips, or holders, and Fig. 22 shows the same index closed up to occupy a minimum amount of thickness, when such is of importance.

35 Fig. 20 is a modification showing a construction such as in Fig. 19 carried out in metal. In this case the ribands 38, 39, 40, 41 are attached to bars such as 83, 84, which in turn are connected by the hinge pin 85 to the raised hinge barrel 86; the distance pieces connecting the riband frames 38, 83, 41 to the cover 61a are formed in this case by means of cranked wires such as 87 hinged as shown at 40 88 to the cover 61a at a plurality of points,

and hinged again at points such as 89 to the ribands 38 to 41.

The main hinge of the book is constructed by means of double hinge pins 90, 91, with an upstanding structure 92 between them carrying the hinge barrel 86, so as to maintain a difference of level between the pivoted points about which the covers and the riband frames turn respectively.

When the covers 61a are closed together 75 the action of the hinge 86 leads to the closing of cranks such as 87 against the covers, and thus again a minimum amount of space is required when the index is closed.

It will be understood that the ribands hold 80 a series of index strips such as 1, or a series of index cards such as are shown in Fig. 15, but in either case the cover is enabled to hold flat with only the thickness of the cards separating them.

In its simplest form an index according to this invention is only the thickness of two layers of sheets, and though in consequence readily flexible, there is no tendency for the strips to mount one upon another.

Also by the use of this invention a very easy method of extracting or replacing a strip in the index concerned is available.

Whilst, above, preferred embodiments of the invention have been described, it will be 95 understood that various modifications may be made without departing from the scope of the invention.

What I claim is:—

1. An index strip provided with a plural- 100 ity of lugs projecting from both longitudinal edges of the strip in staggered relation and each lug formed with one or more lateral projections adapted to engage underholding ribands for securing the strip thereto, the lugs permitting the strip to be secured in close juxtaposed relation with another strip without overlapping therewith.

2. An index strip provided with a plural- 110 ity of lugs projecting from both longitudinal edges of the strip in staggered relation and each lug formed with one or more lateral projections adapted to engage under holding ribands for securing the strip thereto, the lugs permitting the strip to be secured in close 115 juxtaposed relation with another strip without overlapping therewith, and the width of the strip being arranged to correspond substantially to the normal typewriter spacing, whereby entries may be readily made on a 120 plurality of juxtaposed strips in a typewriter.

3. An index strip provided with three project- 125 ing lugs arranged in spaced relation along one longitudinal edge and a pair of project- ing lugs intermediately disposed with respect to the other lugs along the other longitudinal edge, each of the lugs being formed with one or more lateral projections adapted to engage under holding ribands for securing the strip thereto, whereby a strip may be secured 130

in close juxtaposed relation with another strip without overlapping therewith.

4. An index strip provided at each end with a lug projecting from one longitudinal edge, and at least one intermediate lug projecting from the other longitudinal edge, the end lugs being formed with inturned lateral projections and the intermediate lug having a pair of oppositely disposed lateral projections, whereby the strip may be secured to holding ribands and in close juxtaposed relation with another strip without overlapping.

5. An index strip provided with at least three lugs projecting from one longitudinal edge, one of said lugs being disposed at each end of the strip, and a plurality of lugs projecting from the other longitudinal edge arranged in staggered relation to the first-mentioned lugs, the end lugs being formed with inturned lateral projections, and the remaining lugs each having a pair of oppositely disposed lateral projections, whereby the strip may be secured to holding ribands and in close juxtaposed relation with another strip without overlapping.

6. A method of producing index strips consisting in partially slotting a sheet to provide a plurality of juxtaposed index strips, each strip having lugs with lateral projections on their opposite longitudinal edges, and in separating the index portion of the several index strips by a distance equivalent to the normal typewriter spacing, whereby entries may be readily made on the index strips prior to their detachment from the sheet for insertion in an index.

7. In combination, a plurality of index strips provided with a plurality of lugs on both longitudinal edges of the strip, said lugs on the two sides being in staggered relation, and each lug formed with lateral projections, and a support sheet carrying a plurality of spaced-apart holding ribands, the lateral projections on the lugs engaging under the holding ribands to secure the several strips thereto and the lugs constituting means whereby the strips may be held in close juxtaposed relation without overlapping.

8. In combination, a plurality of index strips each provided with a plurality of lugs on both longitudinal side edges of the strip, said lugs on the two sides being in staggered relation and each lug formed with one or more lateral projections, and a support sheet carrying a plurality of spaced-apart holding ribands, the lateral projections on the lugs engaging under the holding ribands to secure the several strips thereto and the lugs constituting means whereby the strips may be held in close juxtaposed relation without overlapping, and means at one edge of the support sheet for enabling the sheet to be secured in a binder.

9. A strip index in book form comprising

index strips each provided with a plurality of lugs on both longitudinal edges of the strip, said lugs on the two sides being in staggered relation and each lug formed with one or more lateral projections, a folder comprising a pair of hinged covers, and a distancing support frame for the strips mounted between the covers and carrying spaced-apart holding ribands secured between two opposite edges of the frame, the lateral projections on the lugs of the strips being engaged under the ribands, whereby manipulation of the strips is facilitated.

10. A strip index in book form comprising index strips each provided with a plurality of lugs on both longitudinal edges of the strip, said lugs on the two sides being in staggered relation and each lug formed with one or more lateral projections, and a folder comprising a pair of hinged covers, a distancing support frame for the strips mounted on each cover, the frames each carrying spaced-apart holding ribands secured between two opposite edges of the frame so as to raise the ribands from the covers, and the lateral projections on the lugs of the strips being engaged under the ribands whereby manipulation of the strips is facilitated.

11. A strip index in book form comprising index strips each provided with a plurality of lugs on both longitudinal edges of the strip, said lugs on the two sides being in staggered relation and each lug formed with one or more lateral projections, a folder comprising a pair of hinged covers, a distancing support frame for the strips mounted between the covers and carrying spaced-apart holding ribands secured between two opposite edges of the frame, the lateral projections on the lugs of the strips being engaged under the ribands, and a rigid plate mounted for adjustment on the said ribands to facilitate removal of any index strip while being locatable to secure the index strips in proper position.

12. A strip index in book form comprising index strips each provided with a plurality of lugs on both longitudinal edges of the strip, said lugs on the two sides being in staggered relation and each lug formed with one or more lateral projections, a folder comprising a pair of hinged covers, a collapsible distancing support frame for the strips mounted on each cover, the frames each carrying spaced-apart holding ribands secured between opposite edges of the frame, under which ribands the lateral projections on the lugs of the strips are engaged, and means operable automatically on the covers being opened to actuate the distancing frames so that the index strips are raised from the covers, whereby to facilitate manipulation of the strips and, when the covers are closed, to cause the frames to collapse.

13. In combination, an index strip pro-

vided with a plurality of lugs on both longitudinal edges of the strip, said lugs on the two sides being in staggered relation and each lug formed with one or more lateral 5 projections adapted to engage under holding ribands for securing the strip thereto, the lugs permitting the strip to be secured in close juxtaposed relation with another strip without overlapping, and an index card 10 mounted on the strip whereby the strip is adapted for use as a holder for the card.

In testimony whereof I affix my signature.
RICHARD FITZ POWER.
